United States Patent Office.

V. R. DAVID, OF SANDWICH, ASSIGNOR TO HIMSELF AND D. R. POMEROY, OF PLANO, ILLINOIS.

Letters Patent No. 78,070, dated May 19, 1868.

IMPROVED METHOD OF INSERTING ARTIFICIAL TEETH.

The Schedule referred to in these Letters Patent and making part of the same.

TO ALL WHOM IT MAY CONCERN:

Be it known that I, V. R. DAVID, of Sandwich, in the county of DeKalb, and State of Illinois, have invented a new and improved Method of Inserting Artificial Teeth; and I do hereby declare that the following is a full, clear, and exact description of the construction and operation of the same, reference being had to the annexed drawings, making part of this specification, in which—

Figures 1 and 2 show the artificial teeth in connection with the artificial plate to which they are attached in perspective. Parts lettered as follows: A, teeth; B, plate; C C, wings; D D, chambers.

I construct my improvement, as shown by figs. 1 and 2, substantially the same as in ordinary practice by dentists; the plate B being of rubber, or any suitable material, except that in ordinary practice a difficulty arises by the inability of the wearer to retain the lower plate in proper position. To obviate this I construct my plate in proper form to fit the lower jaw, and extend that portion of the plate which lies outside of the jaw, and opposite those teeth known as the molars and cuspids or double teeth, in the form of two wings or flanges, as shown at C C, which, for convenience, I will call wings. These wings I allow to extend in nearly a horizontal position, in width from one eighth of an inch to one half of an inch, or as far as the size of the mouth will reasonably permit; and from the rear end of the plate, as far forward as the teeth known as the cuspids, they being, when first formed, next to the molars, say from one-eighth to one-fourth of an inch in thickness, and diminishing in thickness towards the edge, so that they may have, when completed, a thin but not sharp edge. I now remove from the under side of these wings a portion of the material, extending from a line directly under the outside of the molars and cuspids to the outside of the wings, to prevent the outside portion of the wings from resting upon the jaw and causing irritation, and to form two chambers under the plate, as shown at D D.

The operation of my improvement is as follows: Upon closing the mouth, every portion of the under side of the plate, except the wings, is made to press upon the lower jaw, and the insides of the cheeks are pressed by the muscles opposite the molars, against the outer edges of the wings C C, thus forming two chambers underneath the wings C C, from which chambers the air can be exhausted by the operation of the mouth, thus forming two vacuums underneath the wings. Now, upon opening the mouth, the inside of the cheek still pressing the edges of the wings C C, and preventing the air from entering the chambers D D, the vacuum is retained, and the pressure of the atmosphere upon the top of said wings, or upon the outside of the cheeks opposite the vacuums, pressing the cheeks against the edge of and over the tops of the wings C C, holds the plate in position while the mouth is open. Now in the attempt to close the mouth, as in biting with the incisors or front teeth, the posterior portion of the plate is held down upon the lower jaw by the combined pressure of the atmosphere, and the flexible portion of the inside of the cheeks upon the top of the wings C C, thus preventing the posterior portion of the plate from being raised by the depression upon the incisors or front teeth, and the plate thrown out of position.

What I claim as my invention, and desire to secure by Letters Patent, is—

The wings C C, constructed substantially as and for the purposes specified.
